UNITED STATES PATENT OFFICE

WILEY J. DUNHAM, OF BEREAL, OHIO, ASSIGNOR TO THE DUNHAM COMPANY, OF BEREAL, OHIO, A CORPORATION OF OHIO

DOUBLE-ROLLER PULVERIZER

Application filed May 8, 1929. Serial No. 361,803.

An object of this invention is to provide a suitable flexible connection between the weight carrying frame and the roller carrying frames of a double roller pulverizer.

5 Another object is to avoid excessive wear between the moving parts of these frames.

These and other objects, as will hereinafter appear, are accomplished by this invention which is fully described in the following 10 specification, and shown in the accompanying drawings in which—

Figure 1 is a side elevation of a pulverizer embodying the invention; and

Fig. 2 is a partial enlarged section on the 15 line 2—2 of Fig. 1 showing the connection between the weight carrying frame and a roller carrying frame.

The embodiment illustrated comprises a double roller soil pulverizer having frame 20 members 10 which are secured at each end to a weight carrying frame 11, a tongue 12 or the like being secured to the frame member 10 intermediate to members 11. Each frame member 11 has pivotally mounted thereon a 25 roller carrying frame 13, each of these frames having bearings 14 and 15 in which are journaled shafts (not shown) which carry the soil pulverizing rollers 16 and 16 respectively.

The weight carrying frames 11, one at each 30 end of the pulverizer, are preferably symmetrical with respect to a central vertical line, and are provided with lateral cylindrical extensions 18 and 19. One of these extensions as 19 is adapted to fit into a socket 20 in the 35 roller carrying frame 13, while the cylindrical extension 18 is adapted to rock in front of an abutment 21 which is arcuate in form, and substantially concentric with the axis of the socket 20 and of the cylindrical extension 19.

The frames 11 and 13 are preferably made of cast-iron, and in order to prevent excessive wear between these cast-iron members I have provided wearing strips of steel or the 45 like 22 and 23 which lie between these frames. The steel upon cast-iron thus produces much less wear than would be the case were the cast-iron to rub directly upon cast-iron, and moreover the renewable wearing strips are 50 capable of easy and inexpensive renewal.

With the parts in the position shown in Fig. 1, the frame 11 is disengaged from the frame 13 rocking the former back in a clockwise direction about the "ball" 19 as an axis until the extension 18 will pass out over the top of the strip 23, when frame 11 can be lifted bodily out of engagement with the frame 13. These frames are assembled by a reverse operation, that is, by rocking the member 11 back, inserting the ball 19 into the socket 20, and then rocking the member 11 to the left about the center of the ball 19 as an axis. The side of the member 13 is preferably shown cut away at 13^a.

Thus it will be seen that a very simple and substantial flexible connection has been provided between the frames 11 and 13, and one which can be economically manufactured, and one in which the wearing parts may be easily and inexpensively replaced.

While I have shown and described but a single embodiment of my invention, it is understood that it is capable of many modifications. Changes, therefore, in the construction and arrangement may be made which do not depart from the spirit and scope of the invention as disclosed in the appended claims.

I claim:

1. In a soil pulverizer, a weight carrying frame, and roller carrying frames disposed below the weight carrying frame and rockably mounted thereon, said mounting including a concavely arcuate socket in one frame and a complementary convexly arcuate portion in the other frame and abutting surfaces in said members concentric with said socket for retaining said members assembled.

2. In a soil pulverizer, a weight carrying frame, roller carrying frames disposed below the weight carrying frame and rockably mounted thereon said mounting including a concavely arcuate socket in one frame and a complementary convexly arcuate portion in the other frame and abutting surfaces in said members concentric with said socket for retaining said members assembled, and a wearing strip inserted between said abutting surfaces.

3. In a soil pulverizer, a weight carrying frame, roller carrying frames disposed below

the weight carrying frame and rockably mounted thereon, said mounting including a concavely arcuate socket in one frame and a complementary convexly arcuate portion in the other frame and abutting surfaces in said members concentric with said socket for retaining said members assembled, and a wearing strip inserted between said abutting surfaces and between said socket and arcuate portion.

4. In a soil pulverizer, a weight carrying frame, roller carrying frames disposed below the weight carrying frame and rockably mounted thereon, said mounting including a concavely arcuate socket in one frame and a complementary convexly arcuate portion in the other frame and abutting surfaces in said members concentric with said socket for retaining said members assembled, and wearing strips inserted between said ball and socket and between said abutting surfaces.

5. In a soil pulverizer, a weight carrying frame, roller carrying frames disposed below the weight carrying frame and rockably mounted thereon, said mounting including a concavely arcuate socket in one frame and a complementary convexly arcuate portion in the other frame and abutting surfaces in said members concentric with said socket for retaining said members assembled, and wearing strips inserted between said abutting surfaces, said frames being of cast metal and said wearing strips being of steel.

In testimony whereof, I have hereunto set
my hand this 5th day of April, 1929.

WILEY J. DUNHAM.
